UNITED STATES PATENT OFFICE

2,489,416

MACHINE FOR USE IN MANUFACTURE
OF SHOESHerman A. Imhof, Beverly, Mass., assignor to
United Shoe Machinery Corporation, Flemington, N. J., a corporation of New Jersey

Application December 10, 1947, Serial No. 790,880

39 Claims. (Cl. 12—10.3)

1

The present invention relates to machines for use in the manufacture of shoes and is herein illustrated as embodied in an automatic side lasting machine of the type disclosed in United States Letters Patent No. 1,706,619, granted March 26, 1929, No. 1,999,298, granted April 30, 1935, and No. 2,201,866, granted May 21, 1940, all on applications of Robert H. Lawson.

In the machine of the above noted patents, a shoe supporting jack is provided mounted for movement relatively to the side lasting devices of the machine to enable a shoe on the jack to be presented properly to the lasting devices throughout the length of the shoe. The jack has a shoe supporting cradle pivoted for rocking movement about the lengthwise axis of the shoe thereon so that both sides of a shoe bottom may be operated upon simultaneously, the operating pressures of the devices against the shoe bottom being balanced about the pivot of the cradle. In the prior machine the shoe is applied to the jack and presented to the lasting devices as a necessary manual operation. After the lasting has been completed the shoe is removed from the jack as a second necessary manual operation.

An object of the present invention is to provide a machine for operating upon shoes having a shoe supporting jack in which the number of necessary manual operations is reduced to a minimum and more particularly in which it is unnecessary to remove a shoe manually from the machine, the jack being so constructed as to admit unobstructed downward passage of a shoe released from the jack. With such a machine the operator is relieved of a substantial proportion of the effort required in maintaining continuous production.

A further object of the invention is to provide a machine of the type referred to having devices operating with a pressure applied simultaneously to opposite marginal portions of a shoe in which the pressures of the operating devices on the shoe may more readily be balanced and in which the operation of said devices is rendered more effective than in prior machines as well as more readily regulated for use with shoes having relatively great lengthwise curvatures. Still further objects are to improve the construction and to simplify the mode of operation of a machine of the type referred to in such a way as to enable the machine to be attended by a relatively unskilled operator and, at the same time, to require less attention and exertion on the part of the operator than heretofore.

One difficulty in the operation of the machine 55 panying drawings, in which,

2

disclosed in the prior patents is that the shoe is engaged at the heel end by a last pin arranged to be received by the pin hole of the last, after which the last pin is moved bodily with the shoe until the toe of the shoe is engaged with a toe rest against which the shoe is clamped by continued movement of the last pin. At the end of a lasting operation on the shoe the last pin is retracted from the toe rest to release the shoe, the heel end of the last on which the shoe is mounted still being impaled by the last pin. It is then necessary for the operator to remove the shoe manually by lifting it from the last pin. In some instances the removal of the shoe is resisted by binding action between the last pin and a metal sleeve lining the last pin hole as a result of canting the shoe on the last pin while lifting the shoe.

To avoid these difficulties, in accordance with 20 an important feature of the invention, the present machine has a shoe supporting jack provided with heel and toe engaging members in which one of the members is mounted upon a horizontally offset arm to admit unobstructed downward 25 passage of a shoe from a position engaging the heel and toe members. Thus, when the heel and toe engaging members act only at the outer surface of a shoe being operated upon, without the use of a last pin in the jack, the action of gravity 30 alone is sufficient to cause the shoe to be discharged from the machine. As a result, it is necessary only for an operator to apply a new unlasted shoe to the machine after which the next operation will be performed automatically 35 and the completed shoe will be ejected without special attention. Preferably the heel and toe engaging members are carried by a bar in the jack from which they are offset horizontally so that a sufficient space for downward passage of 40 the shoe when released from the jack will be provided beneath said members.

To assist in removing the shoe from the machine a chute is arranged on the jack beneath the heel and toe engaging members to receive the shoe after the operation is completed, the chute being directed to a suitable transfer apparatus or to a packing case as convenience may indicate.

These and other features of the invention are embodied in a machine having the devices, combinations and arrangements of parts hereinafter described and claimed, the advantages of which will be readily understood from the following description taken in connection with the accom-

Fig. 1 is a view in left side elevation of an automatic shoe side lasting machine embodying the features of the present invention;

Fig. 25 is a similar view of the same parts shown in positions taken while the heel clamp is engaging and locked against a shoe.

The machine illustrated in the drawings is an automatic side lasting machine of the type illustrated in the patents referred to, acting automatically and simultaneously upon opposite bottom margins of a shoe. A shoe in condition to be operated upon by the machine comprises an upper 2 (see Fig. 2) mounted on a last 4 having temporarily attached thereto a ribbed insole 6.

To last and secure the marginal portions of the upper to the bottom margin of the insole 6, the machine has two pairs of lasting grippers 8, best shown in Figs. 1 and 4, stapling units 10 and rib

guided presser feet or stapling anvils 12, each acting with pressure against the corresponding bottom margin of the shoe. During the operation of the machine on a shoe the gripper and stapling units are moved toward and from each other by the movement of the presser feet along the inner surfaces of the insole ribs as the operation progresses step-by-step from the shank of a shoe toward the toe end, downward and outward pressure of the presser feet on the insole within the rib acting to guide the operations of the lasting units.

The machine of the patents above identified is provided with a toe rest and a last pin on which a shoe is secured in position on the jack. The toe rest and last pin are mounted for relative movement on a cradle pivoted to rock about an axis extending lengthwise of the shoe on the jack. To support the cradle mounting, the jack has a frame and a frame supporting structure comprising a horizontally extending link similar to that indicated in the drawings at 14, one end of which link is pivotally connected to the frame and the other end of which is pivotally connected to the upper end of an arm 16. The arm 16, in turn, is pivotally mounted upon a base to swing about an axis extending transversely to the direction of feed and substantially parallel with the plane of the bottom of a shoe supported on the jack. The axis of the pivots connecting the link 14 with the jack frame and arm 16 are also parallel with the axis about which the base swings during feeding movement of the shoe. With this supporting structure proper positioning movements are given to the shoe during lasting operations to present the shoe properly as it is fed and the mechanism for imparting these movements are similar to those disclosed in the patents.

By reason of the manner in which the shoe is attached to the jack in the machine of the patents, it is necessary to lift the shoe manually from the last pin after being released from engagement with the toe rest. While the mere lifting of the shoe from the last pin ordinarily presents no serious obstacle it does require some effort on the part of the operator and occasionally may delay the presentation of a new shoe to the jack unless the removal from the last pin is carefully accomplished, avoiding the possibility of cramping the last pin within the last pin hole of a last. Thus, if an attempt is made to remove the shoe horizontally and the toe end of the shoe is lifted higher than the heel end, the metal ferrule in the last pin hole may bind against the last pin. In this way the removal of the shoe may be retarded, resulting in loss of time and annoyance and requiring particular attention on the part of the operator to complete the removal of the shoe before a new shoe may be substituted.

The jack in the machine embodying the present invention has a toe rest similar to that of the prior machine but instead of employing a last pin to support the heel end of the shoe, the heel end is clamped in the present machine externally and the heel and toe engaging members of the toe rest and heel clamp are offset horizontally from their supporting structure to admit unobstructed downward passage from clamped position of a shoe under natural gravitational force when released from the jack. The heel clamp is in the form of a block 18 having a reentrant V-shaped recess provided with decreasing width in a downward direction to surround and prevent downward movement of the heel of a shoe. The toe rest is formed from a

block 20 and is cupped to fit the upper surface of a shoe toe and to extend upwardly above the bottom surface of the shoe when the shoe is presented to the jack in upside-down relation, thus preventing displacement of the shoe under lengthwise clamping action. Accordingly, the toe rest has an upwardly extending surface 22 inclined slightly toward the heel end of the shoe.

The shoe engaging members are mounted and connected together on an inclined bar 24 and the heel clamp is movable along the bar relatively to the toe rest to secure or release the shoe from the jack.

To admit unobstructed downward passage of a shoe under the action of gravity from a position between the shoe engaging members, the members are offset horizontally from the bar 24. For connecting the toe rest to the bar and for supporting the toe rest end of the bar the toe rest block 20 is clamped to an arm 26 made fast to the bar. The arm 26 is offset along its length and carries a guideway mounting block 28. The heel clamp is pivoted on an upwardly projecting offset arm 30 mounted for rocking movement on a bolt 32 passing through a slot in a block 34 clamped to the heel end of the bar 24.

The toe rest, heel clamp, offset supporting arms 26 and 30, and the bar 24 in the illustrated machine constitute a shoe supporting cradle which is pivoted for rocking movement about the lengthwise axis of a shoe clamped in the jack, the shoe being rocked and subject to linear movement transversely of its lengthwise axis in a manner similar to that disclosed in the patents above identified. The mounting for the cradle which enables the shoe to be subject to linear movement transversely of its lengthwise axis comprises the guideway block 28 and angularly disposed rolls 36 and 38. The axis of roll 36 extends parallel to the lengthwise axis of the shoe and the axis of roll 38 extends at right angles thereto in a vertical direction. The axis pivots or studs about which the rolls rotate are indicated at 39 and are secured directly to the upper end of an arm 40 constituting the main jack frame, the stud for the roll 36 permitting rocking movement of the cradle with the cradle in any transverse position.

The heel end of the shoe supporting cradle is maintained in position by cantilever action, one fulcrum of which includes the roll 38 at the toe end of the cradle, acting in the guideway block 28 enclosing the rolls 38 and the other fulcrum of which comprises a pair of spaced vertical arcuate guideway plates 42 and 44 secured to flanges projecting upwardly from the jack frame. A pair of rolls 46 and 48 project from the central portion of the cradle in angular relation to each other and engage the plates 42 and 44, having mounting studs 50 and 52 (see Fig. 4) carried by an offset arm 54 secured in turn to the cradle bar 24. The arrangement is such that downward pressure at the heel end of a shoe on the jack is translated into horizontal pressures between the rolls 46, 48 and the plate 42 in one direction and the roll 38 and the guideway block 28 in the other direction to form a supporting couple of forces. With this construction the space beneath the heel end of a shoe in the jack is entirely free and unobstructed so that when the shoe is released, even though the toe end should engage the plate supporting flanges of the jack frame, the heel end of the shoe will continue to drop by action of gravity until it is entirely cleared from the toe rest. The location of the

plates also is such as to permit free rocking and transverse movements of the cradle in the jack frame. With the shoe thus free to drop there is little obstruction to downward movement of the shoe from the entire jack supporting structure.

To facilitate removal of the shoe by the action of gravity clear of the jack supporting structure, a shoe conducting chute is provided beneath the 10 clamped position of the shoe. A shoe released from the jack is received within the chute and slides out of the machine clear of the jack. The chute is in the form of a series of parallel bars 15 56 having their forward ends bent away from each other and their central portions welded to a pair of arms extending from a block 58 secured to the upper surface of the jack supporting link 14. The lower ends of the bars are extended to the left as far as necessary to clear the jack supporting structure and to enable use of a packing case or other shoe receiver into which the chute empties. To brace the upper ends of the bars 20 they are welded to a second pair of arms also projecting from the block 58.

25 In the embodiment of a further feature of the invention, the heel clamp 18 is so mounted on the inclined bar 24 by the arm 30 and a slide connection that the heel clamp moves proportionately to higher positions along the bar with decreasing sizes of shoes. A shoe is thus maintained in a level position regardless of shoe size, a lower depth of the shoe heel for small sizes being compensated for by the higher position of the heel clamp. For mounting the offset arm 30 30 the pivot bolt 32 passes through a pair of spaced slide blocks 60 best shown in Figs. 18 and 21, mounted between surfaces of guideways formed between a plate 62 secured to the undersurface of the slot in the block 34 and the horizontal 35 flanges of angular members 63 secured to the lower edge of the slot with vertical flanges extending downwardly into a vertical portion of the slot in the block 34. As the arm 30 rocks about the pivot bolt 32 the pivot bolt moves along the 40 slot carrying the slide blocks 60. The arrangement is such that as the heel clamp moves upwardly in an inclined path to maintain a level position in a clamped shoe regardless of shoe size, it approaches closer to the toe rest.

50 To insure maintaining a level position of the heel clamp and to cause the pivot bolt 32 to move as the arm 30 is rocked, a downward extension on the outer of two plate portions of the arm is pivotally connected at 64 to a link 65 which in 55 turn swings about a pivot screw 66 on the block 34. The pivot bolt 32 has an enlarged disk-like head screwed to one side of an arm 68 mounted outside the outer plate portion of arm 30. A downward extension of the arm 68 is pivotally 60 connected at 70 to a link 72 rotatable about a pivot screw 73 on the block 34. The upper end of arm 68 is provided with a roll 74 (see Figs. 2 and 6) engaging a flat surface 76 on the heel clamp below a pivot pin 78 connecting the heel 65 clamp with the arm 30. The arms 30 and 68 are so arranged and the pivots 64 and 70 connecting the respective links 65 and 72 are so located that the centers of the pin 78 and the roll 74 move the same distance toward or from the toe rest as 70 the bolt 32 moves within the slot of the block 34.

To move the heel clamp toward the toe rest in clamping a shoe the slide blocks 60 and pivot bolt 32 are acted upon yieldingly by a spring to draw it toward the toe rest. For this purpose the central part of the bolt passes through an angularly

disposed link 82 (see Figs. 18, 21, 23 and 24). The link 82 is formed with a flat upper surface which, during the movement of the bolt 32 toward the toe rest, engages the undersurface of the plate 62 and slides along this plate (Fig. 25). The link 82 also is formed with spaced, downwardly extending portions through which pass a pin 84 connecting a spring actuated link 86 interposed between the spaced portions of the link. The link, in turn, is pivotally connected at 88 with a rod 90 slidably mounted within the bar 24. The rod 90 is connected to the central member 92 of a Bowden wire, the sheath of which is indicated at 94 (see Figs. 3 and 11). One end of the sheath is clamped to the upper end of the inclined bar 24 and the other end is clamped to a bracket 95 within the jack frame 40. Within the jack frame 40 the central member 92 of the Bowden wire is connected to a spring pressed plunger 95 having coiled about it the spring, indicated at 98, of the compression type. The upper end of the compression spring acts upon a shoulder in the bracket 95 and the lower end against a collar 100 on the plunger 96. By mounting the spring pressed plunger within the jack frame rather than in the bar 24, as in the patented machine, the weight of the cradle is materially reduced and the clamping action of the shoe engaging members rendered more responsive to the controls than in the patented machine.

To lock the heel clamp in a shoe clamping position against separation from the toe rest, the bolt 32 is surrounded at either side of the link 82 by similar but oppositely shaped pawls 102 (see Fig. 22) having downwardly directed detents engaging spaced ratchets formed by upstanding teeth along the apex of the angle between the vertical and horizontal flanges of the angular members 63. The detents on the pawls are pressed yieldingly against the ratchets by spring pressed plungers 104 mounted in openings in the pawls 102 in proper positions to engage and slide along the undersurface of the plate 62 during movement of the slide blocks 60 toward and from the toe rest.

At the end of a lasting operation on a shoe the heel clamp is unlocked and moved away from the toe rest to release a shoe by mechanism generally similar to that employed to actuate the last pin in the prior patented machine. After being moved away from the toe rest the heel clamp is retained in a position spaced from the toe rest. For unlocking and moving the heel clamp of the present machine the plunger 96 is actuated against the force of the spring 98, moving the rod 90 through its Bowden wire connection and the link 82 toward the left as seen in Fig. 24. Leftward movement of the link 82 first causes the link to swing downwardly about the bolt 32 bringing the undersurface of a recessed portion in the link against laterally projecting lugs on the pawls 102. Continued leftward movement of the rod 90 presses the lugs on the pawls downwardly and raises the detents from their ratchets, thus unlocking the heel clamp. Still further leftward movement forces the heel clamp away from the toe rest to its extreme spaced position illustrated in Fig. 24.

To retain the heel clamp in its extreme spaced position from the toe rest and to hold the pawls out of engagement with the ratchets the downwardly extending portions of the spring connected link 82 are engaged by a sliding latch 106 mounted in grooves between the sides of a slotted block 108 secured in vertical slot of block

34 by screws 66 and 73. The latch 106 is actuated yieldingly toward a raised position by a coil spring 112 stretched between a pin on the latch and a pin on the block 108.

After presenting a shoe to the jack the link 82 is released from the latch 106 and the heel clamp is moved into engagement with the shoe. To release the link 82 the latch has a central cut and carries a transverse pin 114 against which the inner end of an actuating lever 116 acts within the central cut. The lever 116 is fulcrumed on a pin 118 and is provided with a handle 120 clamped to a block 122 in turn secured to the outer arm of the lever.

Due to the construction of the cradle with the toe rest and heel clamp in offset relationship to the bar 24 on which they are mounted, the weight of the bar tends to rock the cradle to one side. To balance the weight of the bar and cradle mounting arms, the cradle is acted upon by a spring 124 (see Figs. 4, 6 and 11), one end of which surrounds a pin 126 carried by the upwardly extending arm of a cradle shifting lever 128. The other end of the spring is hooked about a pin 130 projecting from the toe rest supporting arm 26. This spring not only resists rocking movement of the cradle out of balanced position but also aids in centering the cradle on the jack frame in a direction transverse to the axis of rocking movement.

The machine of the patents above identified is provided with mechanism including a cam shaft mounted on the jack frame for changing the position of the shoe supporting cradle transversely of its rocking axis during the lasting operation to accommodate shoes of varying degrees of lengthwise curvature. By so doing, the upward pressure of the shoe against the presser feet 12 of the lasting units is more equally balanced than would be if the rocking axis were maintained in fixed relation to the shoe. For operating on right and left shoes it is necessary to reverse the positioning movement of the cradle in the jack frame and for this purpose connections for rotating the position changing cam on the shaft are disconnected and reconnected to bring a reverse portion of the cam into operation. In some instances shoes are encountered having extremely large lengthwise curvature with which it is necessary in the patented machine to substitute a different cam for the one in the jack frame in order to increase the range of cradle movement transversely of its rocking axis sufficiently to maintain the pressures on the presser feet balanced throughout the length of the shoe. In the illustrated machine necessity of changing cams in the jack frame to accommodate shoes of widely varying lengthwise curvature is avoided and suitable manual adjustments are provided in the cam actuated connections for accomplishing the same purpose.

To accommodate shoes of widely varying lengthwise curvature in the machine of the present invention, the lever 128 is connected with the cradle through a link 132 surrounding the pin 126 at one end and a pin 134 (see Fig. 13) carried by the offset arm 26 in approximate alignment with the axis of the roll 36 and the lever is connected through connections adjustable both for changing the range of transverse movement imparted to the cradle as well as for shifting the limits of transverse movement of the cradle without changing its range of movement. Thus, if a shoe is encountered having a relatively large transverse curvature a greater range of trans-

verse movement must be imparted to the cradle but since most of the movement necessary between the shoe and the mounting of the cradle in the jack frame is at one side of the point at which a lasting operation is started, it is necessary, in addition, to shift the limits of transverse movement of the cradle in the jack frame more or less to one side of a central position. The limits of the transverse movement also must be reset without changing the range of movement when the cradle positioning movement is reversed for operation on a left shoe after operating upon a right shoe and vice versa, since the direction of curvature in a left shoe is opposite to that in a right shoe.

To change the range of transverse movement imparted to the cradle in the jack frame, the lever 128 is fulcrumed on a rock shaft 136 (see Figs. 4, 11 and 13) mounted in bearings projecting from the rearward side of the jack frame. The lower arm of the lever 128 is grooved (Fig. 5) and has slidingly mounted therein a block 137 perforated to receive the rearward end of a bolt 138 adjustably clamped within a slot in an arm 140 clamped to one end of a rockshaft 142 rotatable in an elongated bearing sleeve formed on a fulcrum supporting member or arm 144. The arm 144 is rotatable loosely on a shaft 146 and has a downwardly extending portion, the lower end of which has clamped to it two pairs of perforated plates 148. The perforations in the plates 148 are of conical shape, best shown in Fig. 10, and are disposed to form receivers for balls 150 spaced to engage the flange of either of a pair of cradle movement limit resetting collars 152 adjustably mounted on a manually actuated rotatable threaded shaft 154. The balls 150 thus act as a follower engaging the peripheries of the collars 152.

During operation of the machine on a shoe, movements are imparted to the cradle moving lever 128 through the clamp bolt 138 to the arm 140 and shaft 142. At the opposite end of the shaft 142 is pinned a gear segment 156 meshing with a similar segment of slightly larger radius 158 pinned to the shaft 146 forming a part of a bell crank identified by the same reference character. A downwardly extending arm of the bell crank 158 carries a cam roll 160 engaging a slot in a cradle moving cam 162 secured to a hollow shaft 164 rotatably mounted in the jack frame 40. The hollow cam shaft 164 is given a part of a complete rotation less than 180° during each operation of a shoe by mechanism to be more fully described hereinafter. For a right shoe one part of the cam is effective to move the roll 160 and for a left shoe an opposite part of the cam is effective. The shape of the cam along the parts rendered effective for right and left shoes is such as to reverse the transverse cradle positioning movement.

In order to reverse the cradle movement, the cam 162 is manually disconnected from the cam shaft 164 and is rotated 180° with relation to it. For this purpose the hollow shaft 164 has clamped to its end, opposite the cam, a cradle transverse movement reversing arm 166 provided with a spring pressed locking plunger 168 arranged to enter either of two holes located at diametrically opposite points in a disk 170 secured to the hub of a pulley 172 through which the hollow shaft 164 passes. The plunger has a knurled handle to retract it from the holes in the disk 170. When the plunger is retracted from the disk the cam is disconnected

from the shaft and when the arm 166 is rotated relatively to the disk 170 the cam 162 is rotated relatively to the pulley 172, whereupon it is reconnected in reversed position.

5 The pair of limit resetting collars 152 are connected for rotation with the cam 162 through a pair of pins 174 projecting at right angles to the plane of the respective collars into loose fitting openings in the cam 162. The collars are oppositely dished and their hubs arranged to project in opposite directions from each other with internal threads of opposite hand to receive the oppositely threaded portions of the shaft 154. When the shaft 154 is rotated it therefore displaces the collars 152 in opposite directions so that when the arm 166 is rotated for reversing the cradle shifting cam 162 one collar or the other will engage the balls 150 in different relations. The rims of the collars are beveled at their ends and extend into close proximity to each other through an arc of approximately 180° so that no difficulty will be encountered in rotating the collars past the balls 150.

To shift the limits of transverse cradle movement without changing the total range and in addition to being reversed by rotation of the arm 166, the threaded shaft 154 is rotatable concentrically within the hollow shaft 164 and has secured to its forward end a knurled adjusting wheel 175. When the hollow cam shaft 164 is rotated to reset the limits of transverse cradle movement between operations on left and right shoes the threaded shaft moves with it so that no displacement occurs between the collars 152, the collars rotating with the cam 162 and hollow shaft. When the adjusting wheel is rotated the collars will shift the follower balls 150 and the fulcrum arm 144. Shift of the fulcrum arm will move the cradle in the jack frame to different starting positions.

When the collars have their rims displaced, the limits of movement of the cradle shifting lever will be reset in reversing the transverse movements of the cradle for a right or a left shoe. This is accomplished by a movement of the fulcrum arm 144 for a lever comprising arm 140, rockshaft 142 and segment 156, causing the segment 156 to be turned about the segment portion of lever 158. The fulcrum lever 144 is then retained in position, the rim in each disk being the same shape throughout a cycle.

When a change is made in the range of transverse movement of the cradle relatively to its lengthwise rocking axis, the clamp bolt 138 is loosened and is moved along the slot in the lever 140 to change the effective lengths of the arm 140 and the lower arm of the cradle shifting lever 128. To provide a convenient reference point for the position of the adjusting bolt the bolt carries a rectangular washer 176 having an indicating pointer cooperating with a series of scale marks 178 on the arm 140.

The hollow cam shaft 164 is rotated in a manner similar to that of the cam shaft in Patent No. 2,201,866 by a cord secured to a rotating drum in the base of the machine and passing from the drum over guiding pulleys in the jack supporting structure and around the pulley 172. After the lasting operation on a shoe is completed, the cam shaft is rotated in a reverse direction, returning it to its initial position. During the reverse rotation of the cam shaft the shoe is released from the jack and the parts reset for a new operation.

75 To release the shoe from the jack automatic-

cally, the hollow shaft 164 actuates the plunger 96 against the action of its spring 99. To this end the hub of the pulley 172 is provided with a series of gear teeth 178 (see Fig. 3) which mesh with the teeth on a segment 180 rotatable about a pin 182 in the jack frame 40. The segment 180 has pivotally connected with it a link 183 provided at its upper end with a pin 184 engaging the lower end of the spring pressed plunger 96. The lower end of the plunger has a shoulder and a downwardly extending finger portion. When the link 183 is lowered the pin 184 engages the shoulder in the plunger and upon upward movement of the link the plunger is raised, the heel clamp is unlocked and moved away from the toe rest in a manner already outlined. After latching the heel clamp in its position separated from the toe rest the pin 184 rides against the beveled upper end of an adjustable plate 186, clamped to the jack frame to disengage the pin thereon from the shoulder on the plunger, thus releasing the plunger for yielding operation of the heel clamp when the heel clamp is again released.

To release a shoe from the jack manually without waiting for automatic releasing movement at the end of a lasting operation the jack frame has projecting from it a hand lever 187 fulcrumed on a pin 188 and arranged with its innermost arm beneath the lower end of the plunger 96. Downward movement of the projecting arm of the lever 187 acts to raise the lower end of the plunger 96 in the same manner as in the automatic releasing action. The manual releasing lever is normally held in inoperative position by a spring 190 coiled about the hub of the lever 187 and acting on the lever at one end and on the jack frame at its other end.

The nature and scope of the invention having been indicated and a specific embodiment having been described, what is claimed is:

1. In a machine for operating upon the bottom margins of shoes, a shoe supporting jack having heel and toe engaging members to secure the shoe in the jack, in combination with a horizontally offset arm on which one of said members is mounted to admit unobstructed downward passage of a shoe under the action of gravity from a position between the engaging members.

2. In a machine for operating upon the bottom margins of shoes, a shoe supporting jack having heel and toe engaging members to secure the shoe in the jack, in combination with a bar from which said members are offset horizontally to admit unobstructed downward passage of a shoe under the action of gravity when released from the jack.

3. In a machine for operating upon the bottom margins of shoes, a shoe supporting jack having heel and toe engaging members to secure the shoe in the jack, in combination with a bar on which one of said members is movable relatively to the other to clamp and release a shoe on the jack and from which said members are offset horizontally to admit unobstructed passage of a shoe under the action of gravity at one side of the bar when released from the jack.

4. In a machine for operating upon the bottom margins of shoes, a jack having a heel clamp and a toe rest, in combination with a bar connecting the heel clamp and toe rest, and arms on the bar carrying the heel clamp and toe rest in horizontally offset relation to the bar to admit unobstructed downward passage of a shoe

under the action of gravity from a clamped position between the heel clamp and toe rest.

5. In a machine for operating upon the bottom margins of shoes, a shoe supporting jack having heel and toe engaging members to secure the shoe in the jack, in combination with a horizontally offset arm on which one of said members is mounted to admit unobstructed downward passage of a shoe under the action of gravity from a position between the engaging members and a chute arranged beneath the shoe on the heel and toe engaging members to receive the shoe when released from the jack.

6. In a machine for operating upon the bottom margins of shoes, a jack frame, a cradle and a heel clamp and a toe rest on the cradle, in combination with mounting means for one end and the central portions of the cradle on the jack frame arranged to support the other end of the cradle by cantilever action while guiding the cradle to enable relative rocking movement on the jack frame of a shoe on the cradle about the lengthwise axis of the shoe as the operation on the shoe bottom progresses.

7. In a machine for operating upon the bottom margins of shoes, a jack frame, a cradle and a heel clamp engaging a shoe externally and a toe rest on the cradle, in combination with mounting means including a pivot in the jack frame on which the cradle rocks about the lengthwise axis of a shoe thereon, and guiding means along one end of the cradle and guideway plates on the frame along the central portion of the cradle for preventing downward movement of the other end of the cradle during rocking movement of the cradle.

8. In a machine for operating upon the bottom margins of shoes, a jack frame, a shoe supporting cradle and a heel clamp and a toe rest on the cradle, in combination with mounting means on the jack frame for the toe end of the cradle and guideway plates on the frame along the central portion of the cradle arranged to support the heel end of the cradle by cantilever action while guiding the cradle to enable relative rocking movement on the jack frame of the shoe about its lengthwise axis and linear movement transversely to the lengthwise axis of the shoe as the operation on the shoe progresses.

9. In a machine for operating upon the bottom margins of shoes, a jack frame, a shoe supporting cradle and a heel clamp and a toe rest on the cradle, in combination with mounting means on the jack frame for the cradle, including a pivot on the jack frame on which the cradle rocks about the lengthwise axis of a shoe thereon, a second pivot on the jack frame at right angles to the lengthwise axis of the shoe, rolls on said pivots and guideways at the toe rest end of the cradle enclosing the rolls arranged to enable movement of the cradle transversely of the lengthwise axis of the shoe thereon.

10. In a machine for operating upon the bottom margins of shoes, a jack frame, a shoe supporting cradle and a heel clamp and a toe rest on the cradle, in combination with mounting means on the jack frame for the cradle, including a pivot on the jack frame on which the cradle rocks about the lengthwise axis of a shoe thereon, a second pivot on the jack frame at right angles to the lengthwise axis of the shoe, rolls on said pivots, guideways at the toe rest end of the cradle for the rolls arranged to enable movement of the cradle transversely of the lengthwise axis of the shoe thereon, and an additional guideway and

roll mounting at the central portion of said cradle arranged to support the heel end of the cradle by cantilever action.

11. In a machine for operating upon the bottom margins of shoes, a jack frame, a shoe supporting cradle and a heel clamp and a toe rest on the cradle, in combination with mounting means on the jack frame for the cradle, including a pivot on the jack frame on which the cradle rocks about the lengthwise axis of a shoe thereon, a second pivot on the jack frame at right angles to the lengthwise axis of the shoe, rolls on said pivots, guideways at the toe rest end of the cradle for the rolls arranged to enable movement of the cradle transversely of the lengthwise axis of the shoe thereon, spaced plates and rolls disposed therebetween with their axes in angular relation to each other connecting the central portion of the cradle and jack frame to support the heel end of the cradle by cantilever action while permitting rocking movement of the cradle about the lengthwise axis of the shoe on the jack and linear movement of the cradle on the jack frame transversely of the lengthwise axis of the shoe.

12. In a machine for operating upon the bottom margins of shoes, a jack frame, a shoe supporting cradle and a heel clamp and a toe rest on the cradle, in combination with mounting means on the jack frame for the cradle, including a pivot on the jack frame on which the cradle rocks about the lengthwise axis of a shoe thereon, a second pivot on the jack frame at right angles to the lengthwise axis of the shoe, rolls on said pivots, guideways at the toe rest end of the cradle for the rolls arranged to enable movement of the cradle transversely of the lengthwise axis of the shoe thereon, spaced plates and rolls disposed therebetween with their axes in angular relation to each other connecting the central portion of the cradle and jack frame to support the heel end of the cradle by cantilever action while, permitting rocking movement of the cradle about the lengthwise axis of the shoe on the jack and linear movement of the cradle on the jack frame transversely of the lengthwise axis of the shoe, said heel clamp and toe rest being mounted on offset arms on the cradle to admit unobstructed downward passage of the heel end of a shoe under the action of gravity from clamped position in the cradle.

13. In a machine for operating upon the bottom margins of shoes, a jack frame, a shoe supporting cradle and a heel clamp and a toe rest on the cradle, in combination with mounting means for the cradle on the jack frame including a pivot on the jack frame on which the cradle rocks about the lengthwise axis of a shoe thereon, a second pivot on the frame at right angles to the lengthwise axis of the shoe, rolls on said pivots, guideways at the toe rest end of the cradle for said rolls arranged to enable movement of the cradle transversely to the axis of the shoe, spaced guideway plates and rolls between said plates disposed with their axes in angular relation to each other connecting the central portion of the cradle and jack frame to support the heel end of the cradle by cantilever action while permitting rocking movement about the lengthwise axis of a shoe on the cradle and linear movement of the cradle transversely to the lengthwise axis of the shoe, said heel clamp and toe rest being mounted on offset arms on the cradle to admit unobstructed downward passage of the heel end of a shoe under the action of gravity from clamped position in the

cradle, and a chute on the jack frame beneath the cradle to receive a shoe released therefrom.

14. In a machine for operating upon the bottom margins of shoes, a shoe supporting cradle comprising an inclined bar, a toe rest and a heel clamp on the bar, in combination with an arm connection on the bar for the heel clamp to cause the heel clamp to move proportionately to higher positions on the bar with decreasing sizes of shoes.
15. In a machine for operating upon the bottom margins of shoes, a shoe supporting cradle comprising an inclined bar, a toe rest and a heel clamp on the bar, in combination with an arm to which the heel clamp is pivoted, a slide block on which the arm is mounted, a guideway on the bar for the slide block and a link connected between the arm and the bar to cause the heel clamp to move in an upwardly inclined path to higher positions on the bar as the heel clamp moves toward the toe rest.
16. In a machine for operating upon the bottom margins of shoes, a shoe supporting cradle comprising an inclined bar, a toe rest and a heel clamp on the bar, in combination with an arm to which the heel clamp is pivoted, a slide block on which the arm is mounted, a guideway on the bar for the slide block, a link connected between the arm and the bar to cause the heel clamp to move in an upwardly inclined path to higher positions on the bar as the heel clamp moves toward the toe rest, and a second arm fulcrumed on the block having a bearing on the heel clamp and a second link connected to the second arm to cause the heel clamp to maintain a level position as it moves toward and from the toe rest.
17. In a machine for operating upon the bottom margins of shoes, a shoe supporting cradle comprising an inclined bar, a toe rest and a heel clamp on the bar, in combination with an arm to which the heel clamp is pivoted, a slide block on which the arm is mounted, a guideway on the bar for the slide block, a link connected between the arm and the bar to cause the heel clamp to move in an upwardly inclined path to higher positions on the bar as the heel clamp moves toward the toe rest, and means for locking the slide block to prevent displacement of the shoe when the heel clamp is moved into clamping engagement with a shoe.
18. In a machine for operating upon the bottom margins of shoes, a shoe supporting cradle comprising an inclined bar, a toe rest and a heel clamp on the bar, in combination with an arm to which the heel clamp is pivoted, a slide block on which the arm is mounted, a guideway on the bar for the slide block, a link connected between the arm and the bar to cause the heel clamp to move in an upwardly inclined path to higher positions on the bar as the heel clamp moves toward the toe rest, a spring operatively connected to the slide block to move the heel post toward the toe rest into clamping engagement with a shoe, and a ratchet and pawl for locking the heel clamp against separation from the toe rest.
19. In a machine for operating upon the bottom margins of shoes, a shoe supporting cradle comprising an inclined bar, a toe rest and a heel clamp on the bar, in combination with an arm to which the heel clamp is pivoted, a slide block on which the arm is mounted, a guideway on the bar for the slide block, a link connected between the arm and the bar to cause the heel clamp to move in an upwardly inclined path to higher positions on the bar as the heel clamp moves toward the

toe rest, a spring operatively connected to the slide block to move the heel post toward the toe rest into clamping engagement with a shoe, a ratchet and pawl for locking the heel clamp against separation from the toe rest, and a latch acting to retain the heel clamp in a position spaced from the toe rest.

20. In a machine for operating upon the bottom margins of shoes, a shoe supporting cradle comprising an inclined bar, a toe rest and a heel clamp on the bar, in combination with an arm to which the heel clamp is pivoted, a slide block on which the arm is mounted, a guideway on the bar for the slide block, a link connected between the arm and the bar to cause the heel clamp to move in an upwardly inclined path to higher positions on the bar as the heel clamp moves toward the toe rest, a spring for moving the heel post toward the toe rest, an angularly disposed link through which the spring acts, a ratchet, and a spring-pressed pawl rotatable on the pivot for the heel clamp supporting arm and provided with a lug engaged by the spring connected link to move the pawl out of engagement with the ratchet when the spring is rendered inoperative.

21. In a machine for operating upon the bottom margins of shoes, a shoe supporting cradle comprising an inclined bar, a toe rest and a heel clamp on the bar, in combination with an arm to which the heel clamp is pivoted, a slide block on which the arm is mounted, a guideway on the bar for the slide block, a link connected between the arm and the bar to cause the heel clamp to move in an upwardly inclined path to higher positions on the bar as the heel clamp moves toward the toe rest, a spring for moving the heel post toward the toe rest, an angularly disposed link through which the spring acts, a ratchet, a spring-pressed pawl rotatable on the pivot for the heel clamp supporting arm and provided with a lug engaged by the spring connected link to move the pawl out of engagement with the ratchet when the spring is rendered inoperative, and a latch acting on the spring connected link to retain the heel post in a position spaced from the toe rest and to hold the pawl out of engagement with the ratchet.

22. In a machine for operating upon the bottom margins of shoes, a shoe supporting cradle comprising an inclined bar, a toe rest and a heel clamp on the bar, in combination with an arm to which the heel clamp is pivoted, a slide block on which the arm is mounted, a guideway on the bar for the slide block, a link connected between the arm and the bar to cause the heel clamp to move in an upwardly inclined path to higher positions on the bar as the heel clamp moves toward the toe rest, a spring for moving the heel post toward the toe rest, an angularly disposed link through which the spring acts, a ratchet, a spring-pressed pawl rotatable on the pivot for the heel clamp supporting arm and provided with a lug engaged by the spring connected link to move the pawl out of engagement with the ratchet when the spring is rendered inoperative and mechanism acting on the spring connected link to disengage the pawl from the ratchet and to move the heel post away from the toe rest.

23. In a machine for operating upon the bottom margins of shoes, a jack having a frame, a shoe supporting cradle pivoted in the frame comprising a bar, a toe rest on the bar and a heel clamp movable on the bar toward and from the toe rest, in combination with mechanism for moving the heel clamp toward and from the toe

rest including a spring-pressed plunger in the jack frame and a Bowden wire connection between the cradle and the jack frame.

24. In a machine for operating upon the bottom margins of shoes, a jack having a frame, a shoe supporting cradle pivoted in the frame comprising a bar, a toe rest on the bar and a heel clamp movable on the bar toward and from the toe rest, in combination with mechanism for moving the heel clamp toward and from the toe rest including a spring-pressed plunger in the jack frame and a Bowden wire connection between the cradle and the jack frame and a rotatable shaft in the frame for actuating the plunger against the action of its spring.

25. In a machine for operating upon the bottom margins of shoes, a jack having a frame, a shoe supporting cradle pivoted in the frame comprising a bar, a toe rest on the bar and a heel clamp movable on the bar toward and from the toe rest, in combination with mechanism for moving the heel clamp toward and from the toe rest including a spring-pressed plunger in the jack frame and a Bowden wire connection between the cradle and the jack frame, a rotatable shaft in the frame for actuating the plunger against the action of its spring, and means for disengaging the connection between the rotatable shaft and plunger after the plunger has been moved against the force of its spring.

26. In a machine for operating upon the bottom margins of shoes, a jack having a frame, a shoe supporting cradle pivoted in the frame comprising a bar, a toe rest on the bar and a heel clamp movable on the bar toward and from the toe rest, in combination with mechanism for moving the heel clamp toward and from the toe rest including a spring-pressed plunger in the jack frame and a Bowden wire connection between the cradle and the jack frame, a rotatable shaft for actuating the plunger against the action of its spring, means for disengaging the connection between the rotatable shaft and plunger after the plunger has been moved against the force of its spring, and manually actuated means in addition to the rotatable shaft for moving the plunger against the action of its spring.

27. In a machine for operating upon the bottom margins of shoes, a shoe supporting jack having a frame, heel and toe engaging members for clamping the shoe in position on the jack, and a cradle in which the heel and toe engaging members are mounted, pivoted to the jack frame for rocking movement about the lengthwise axis of a clamped shoe, in combination with arms on which said heel and toe members are offset horizontally on the cradle to admit unobstructed downward passage of a shoe under the action of gravity when released from clamping engagement by said members, and mechanism in the jack frame for moving the heel engaging member relatively to the toe engaging member including a Bowden wire connection between the cradle and the jack frame.

28. In a machine for operating upon the bottom margins of shoes, a jack frame, a shoe supporting cradle mounted for rocking movement in the jack frame comprising a toe rest and a heel clamp movable relatively to the toe rest to clamp and release a shoe from the jack, a spring for moving the heel clamp toward the toe rest, and a latch for preventing movement of the heel clamp toward the toe rest, in combination with a handle lever pivoted on the cradle for releasing

the latch to cause a shoe to be secured on the cradle.

29. In a machine for operating upon the bottom margins of shoes, a jack frame, a shoe supporting cradle comprising heel and toe engaging members and a bar along which said members are mounted for relative movement to clamp and release a shoe from the jack, in combination with a rocking and lineally movable mounting for the cradle on the jack frame including angularly disposed rolls on the frame, an offset arm at one end of the bar on which one of the rolls is mounted substantially in line with the lengthwise axis of a shoe on the cradle and on which another of said rolls is mounted at right angles to said lengthwise axis, a second offset arm displaced from the first offset arm along the bar, and a roll and plate connection between the second arm and the jack frame in which others of said rolls are disposed in angular relation to each other and at right angles to the lengthwise axis of the shoe.

30. In a machine for operating upon the bottom margins of shoes, a jack frame, a cradle having a heel clamp and a toe rest mounted for rocking movement in the jack frame about the lengthwise axis of a shoe secured therein, a bar connecting the heel clamp and toe rest and offset arms on the bar carrying the heel clamp and toe rest to admit unobstructed downward passage of a shoe under the action of gravity from clamped position between the heel clamp and toe rest, in combination with yielding means between the cradle and the jack frame for balancing the weight of the bar and offset arms about the axis of rocking movement of the cradle in the jack frame.

31. In a machine for operating upon the bottom margins of shoes, a jack frame, a shoe supporting cradle comprising heel and toe engaging members and a bar along which said members are mounted for relative movement to clamp and release a shoe from the jack, in combination with a rocking and lineally movable mounting for the cradle on the jack frame including angularly disposed rolls on the frame, an offset arm at one end of the bar on which one of the rolls is mounted substantially in line with the lengthwise axis of a shoe on the cradle and on which another of said rolls is mounted at right angles to said lengthwise axis, a second offset arm displaced from the first offset arm along the bar, and a roll and plate connection between the second arm and the jack frame in which others of said rolls are disposed in angular relation to each other and at right angles to the lengthwise axis of the shoe, and a spring between the cradle and the jack frame for balancing the weight of the bar and offset arms about the mounting rolls.

32. In a machine for operating upon shoes, devices acting with a pressure against opposite bottom margins of a shoe, a jack frame, a shoe supporting cradle, a rocking mounting for the cradle in the jack frame in which the cradle is movable relatively to the jack frame transversely of the axis about which the cradle rocks to balance the pressures of the operating devices about the rocking axis of the cradle, and a cam actuated during operation of the operating devices for changing the position of the cradle transversely to its rocking axis, in combination with a lever connection adjustable to change the range of the transverse movement of the cradle relatively to its rocking axis in the jack frame.

33. In a machine for operating upon shoes, devices acting with a pressure against opposite bottom margins of a shoe, a jack frame, a shoe supporting cradle, a rocking mounting for the cradle in the jack frame in which the cradle is movable relatively to the jack frame transversely of the axis about which the cradle rocks to balance the pressures of the operating devices about the rocking axis of the cradle, and a cam actuated during operation of the operating devices for changing the position of the cradle transversely to its rocking axis, in combination with means for shifting the limits of the transverse movement of the cradle relatively to its rocking axis to enable the pressures of the operating devices to be balanced for right or left shoes.

34. In a machine for operating upon shoes, devices acting with a pressure against opposite bottom margins of a shoe, a jack frame, a shoe supporting cradle, a rocking mounting for the cradle in the jack frame in which the cradle is movable relatively to the jack frame transversely of the axis about which the cradle rocks to balance the pressures of the operating devices about the rocking axis of the cradle, a cam actuated during operation of the operating devices for changing the position of the cradle transversely to its rocking axis, means for rotating the cam a part of a complete rotation during each operation of the operating devices, and means for changing that part of a complete rotation through which the cam is rotated to reverse the transverse movement of the cradle in the jack frame for right and left shoes, in combination with adjustable connections actuated by the position changing cam for resetting the limits of the transverse movement of the cradle when the movement reversing means is actuated for right or left shoes.

40 35. In a machine for operating upon shoes, devices acting with a pressure against opposite bottom margins of a shoe, a jack frame, a shoe supporting cradle, a rocking mounting for the cradle in the jack frame in which the cradle
45 is movable relatively to the jack frame transversely of the axis about which the cradle rocks to balance the pressures of the operating devices about the rocking axis of the cradle, a cam actuated during operation of the operating devices
50 for changing the position of the cradle transversely to its rocking axis, means for rotating the cam a part of a complete rotation during each operation of the operating devices, and means for changing that part of a complete rotation
55 through which the cam is rotated to reverse the transverse movement of the cradle in the jack frame for right and left shoes, in combination with adjustable connections actuated by the position changing cam for resetting the limits of the
60 transverse movement of the cradle when the movement reversing means is actuated for right or left shoes comprising a split collar connected with the position changing cam, separable parts of said split collar being independently adjustable, and manual means for relatively changing the positions of the split collar parts to shift the
65 limits of transverse cradle movement.

36. In a machine for operating upon shoes, devices acting with a pressure against opposite bottom margins of a shoe, a jack frame, a shoe supporting cradle, a rocking mounting for the cradle in the jack frame in which the cradle is movable relatively to the jack frame transversely of the axis about which the cradle rocks to balance the pressures of the operating devices

about the rocking axis of the cradle, a cam actuated during operation of the operating devices for changing the position of the cradle transversely to its rocking axis, means for rotating the cam a part of a complete rotation during each operation of the operating devices, and means for changing that part of a complete rotation through which the cam is rotated to reverse the transverse movement of the cradle in the jack frame for right and left shoes, in combination with adjustable connections actuated by the position changing cam for resetting the limits of the transverse movement of the cradle when the movement reversing means is actuated for right or left shoes comprising a split collar connected with the position changing cam, separable parts of said split collar being independently adjustable, manual means for relatively changing the positions of the split collar parts to shift the limits of transverse cradle movement, levers for moving the cradle on the jack frame, a follower engaging the split collar, and a fulcrum supporting member actuated by said follower on which is mounted one of said levers to cause the limits of transverse cradle movement to be reset when the right or left shoe cam rotation changing means is actuated.

37. In a machine for operating upon shoes, devices acting with a pressure against opposite bottom margins of a shoe, a jack frame, a shoe supporting cradle, a rocking mounting for the cradle in the jack frame in which the cradle is movable relatively to the jack frame transversely of the axis about which the cradle rocks to balance the pressures of the operating devices about the rocking axis of the cradle, a cam actuated during operation of the operating devices for changing the position of the cradle transversely to its rocking axis, means for rotating the cam a part of a complete rotation during each operation of the operating devices, and means for changing that part of a complete rotation through which the cam is rotated to reverse the transverse movement of the cradle in the jack frame for right and left shoes, in combination with adjustable connections actuated by the position changing cam for resetting the limits of the transverse movement of the cradle when the movement reversing means is actuated for right or left shoes comprising a split collar connected for rotation with the cradle position changing cam, and a manually rotatable shaft having right and left-hand threaded portions

for moving the parts of the split cam simultaneously in opposite directions to shift the limits of transverse cradle movement without changing the range of such movement.

- 5 38. In a machine for operating upon shoes, operating devices acting to press simultaneously upon opposite bottom marginal portions of a shoe, a jack frame, a shoe supporting cradle pivoted in the frame to enable rocking movement of the shoe about its lengthwise axis and arranged for movement transverse to the pivot axis to enable the pressures of the operating devices to be balanced, a cam for changing the position of the cradle transversely of its rocking axis as the operation progresses, means for rotating the cam a part of a complete rotation during each operation on a shoe, a shaft on which the cam is mounted and a handle on the shaft arranged to disconnect the cam and change the part of the cam rotation for right or left shoes, in combination with a manually rotatable member concentric with the shaft for shifting the limits of transverse movement imparted to the cradle by the cam.
- 10 39. In a machine for operating upon shoes, operating devices acting to press simultaneously upon opposite bottom marginal portions of a shoe, a jack frame, a shoe supporting cradle pivoted in the frame to enable rocking movement of the shoe about its lengthwise axis and arranged for movement transverse to the pivot axis to enable the pressures of the operating devices to be balanced, a cam, connections actuated by the cam to change the position of the cradle transversely of its rocking axis as the operation progresses, means for rotating the cam a part of a complete rotation during each operation on a shoe, a hollow shaft on which the cam is mounted, and a connection on the shaft arranged to disconnect the cam and rotate the cam relatively to the shaft for right or left shoes, in combination with a manually rotatable shaft within the hollow cam shaft having right and left-hand threaded portions, a pair of collars connected to the first-mentioned cam and arranged with one collar on each threaded portion of the manually rotatable shaft and connections between the collars and the cam to reset the limits of transverse cradle movement on the jack frame when the cam is rotated relatively to the shaft.
